UNITED STATES PATENT OFFICE.

HENRY WIENER, OF NEW YORK, N. Y., ASSIGNOR TO WHITING & DAVIS COMPANY, OF PLAINVILLE, MASSACHUSETTS, A CORPORATION OF NEW YORK.

DESIGN FOR A FRAME FOR A HAND-BAG.

52,092.

Specification for Design.

Patented June 4, 1918.

Application filed March 26, 1918. Serial No. 224,907. Term of patent 7 years.

To all whom it may concern:

Be it known that I, HENRY WIENER, a citizen of the United States, residing in the city, county, and State of New York, have invented a new, original, and ornamental Design for the Frame for a Hand-Bag, of which the following is a specification, reference being had to the accompanying drawing, forming part thereof.

The figure is an elevation of a frame for a hand bag, showing my new design.

I claim:

The design for the frame for a hand bag, as shown.

HENRY WIENER.
